UNITED STATES PATENT OFFICE.

EBEN G. BALCH, OF NEWBURYPORT, MASSACHUSETTS.

PENCIL ERASER ATTACHMENT.

1,267,955.

Specification of Letters Patent. Patented May 28, 1918.

Application filed September 13, 1917. Serial No. 191,158.

To all whom it may concern:

Be it known that I, EBEN G. BALCH, a citizen of the United States, and a resident of Newburyport, in the county of Essex and 5 State of Massachusetts, have invented a new and Improved Pencil Eraser Attachment, of which the following is a full, clear, and exact description.

This invention relates to stationary and 10 has particular reference to lead pencil attachments.

Among the objects of the invention is to provide a novel form or type of attachment for lead pencils including a rubber eraser 15 of unusual length and adaptability for use for a long period of time.

More definitely stated my invention has for its purpose to provide an attachment adapted to be applied to any ordinary pencil 20 and comprises two main rigid parts, one movable relatively over the other and in connection with which is employed an eraser held by the relatively movable part so that a comparatively short length of the 25 eraser is exposed for use, but which when worn down is adapted to be again exposed by movement of the movable member.

With the foregoing and other objects in view the invention consists in the arrangement and combination of parts hereinafter described and claimed, and while the invention is not restricted to the exact details of construction disclosed or suggested herein, still for the purpose of illustrating 35 a practical embodiment thereof reference is had to the accompanying drawings, in which like reference characters designate the same parts in the several views, and in which—

40 Figure 1 is a side elevation of a pencil complete having my improvement attached thereto;

Fig. 2 is a vertical central sectional view 45 of the attachment disconnected from the pencil;

Fig. 3 is a plan view indicating especially the form of the sleeve or movable member of the attachment; and

Fig. 4 is a plan view of the relatively 50 stationary member.

Referring now more definitely to the drawings I show my improvement as comprising a relatively stationary cap member 10 adapted to be applied directly upon the 55 end of a pencil 11 remote from the point 11' thereof where it will be held removably

by friction. This cap member has two distinctly novel features namely the external screw thread 10' extending from one end thereof to the other, the other surface being 60 otherwise of cylindrical form but having a limiting flange 12 at its inner or lower end. The other main novel feature of the cap is shown especially in Fig. 4 and comprises a plurality of spikes or spurs 13 struck and 65 bent upwardly at right angles to the plane of the end 14 thereof. These spurs are preferably all struck upwardly and outwardly from the center of the end 14 whereby each is formed preferably with a relatively 70 sharp point 13' as indicated in dotted lines in Fig. 4. Thus it will be seen that a cruciform slot 15 is left in the central portion of the disk or end 14.

The next main element of my invention to 75 be observed is the sleeve 16, this being a tubular member of practically uniform cross section throughout and having an inner threaded surface 16' coöperating or adapted to coöperate directly with the thread 10' of 80 the cap. The sleeve, therefore, is adapted to be screwed down over the cap until the inner end of the sleeve abuts against the outer edge of the flange 12. The outer surface of the sleeve may be of any suitable form 85 or construction. I find for the purpose of simplicity that a smooth cylindrical surface is suitable, but any portion thereof may be formed polygonal for two purposes, first, to facilitate the rotation of the sleeve upon the 90 cap, and, secondly, to prevent the rolling of the pencil along a desk or table especially if the pencil be round. For this purpose I provide a collar 17 shown as hexagonal in form and secured in any suitable manner to 95 the central portion of the sleeve.

The eraser indicated at 18 may consist of a stick of rubber, or its equivalent, suitable for the erasing of pencil marks as is well known. This eraser is preferably of a size 100 substantially equal to or slightly larger in diameter than the cap 10 so as to fit with a moderate degree of friction within the internally threaded sleeve 16, the resiliency of the eraser serving to permit the movement 105 of the sleeve thereover during the practice of the invention, but with a fairly snug fit between the eraser and the sleeve, the former being held fairly snugly during the erasing action of the device.

110 A device of the character indicated in Figs. 1 and 2 is designed to be made and put

upon the market at a retail price of a few cents and constitutes a distinct article of manufacture adapted for interchange and use on any number of pencils one after another. By this I mean to say that the two main parts 10 and 16, which may be made of metal or some other suitable practically indestructible material may be used indefinitely on any number of pencils and when one 10 eraser wears down after a considerable period of time another may be inserted into the same sleeve. The rubbers themselves may be provided on the market as distinct elements for use in my improved attachment at an exceedingly low cost. When a new eraser is applied to the sleeve and cap the inner or lower end of the eraser is impaled upon the disk 14 so that the spurs 13 enter the end of the eraser and hold the same from rotation so that when the exposed end of the eraser wears down the operator may by giving the sleeve one or more turns provide a fresh exposure for the eraser for 20 subsequent use in a well known manner. It will thus be seen that the eraser is reliably held in place in the sleeve for all purposes and the sleeve is not liable to move accidentally with respect to the cap. The three parts remain in adjusted position permanently with no parts to rattle, wabble or become separated from the rest. By the use 25 of this attachment a person is assured of

always having a suitable eraser for the pencil. The attachment furthermore in addition to being of an ornamental nature and 30 possessing the important features of utility just referred to, serves to give material additional length to a short pencil rendering the same serviceable for a considerable length of time, an item of much importance 35 in view of the fact that so many pencils are discarded and wasted while yet of a serviceable length.

My improvement obviously may be applied to pens or other writing devices by appropriately varying the character of the eraser element.

I claim:

The herein described pencil attachment comprising a cylindrical cap threaded exteriorly and adapted at its inner end to fit on a pencil and having spurs projecting lengthwise from its outer end and within the circumference of said cap, a cylindrical sleeve threaded interiorly its full length and 50 screwed at its inner end on said cap and a cylindrical rubber eraser screwed into and closely fitting the sleeve with the outer portion of said sleeve projecting at its outer end beyond the sleeve and having its inner end entered longitudinally by the end spurs of the cap, as shown and described.

EBEN G. BALCH.
